UNITED STATES PATENT OFFICE

GEORGE W. WILLIAMS, OF BURLINGAME, CALIFORNIA

BUILDING FORM

Application filed December 6, 1929. Serial No. 412,227.

My invention relates to improvements in building forms, and it consists in the combinations, constructions and arrangements hereinafter described and claimed.

5 An object of my invention is to provide a building form that may be used for constructing hollow walls. The principal feature of the invention is to provide a form that can be secured to the top and bottom plates of 10 a wall, the form providing recesses extending vertically for receiving concrete. The hardening of this concrete in the recesses forms columns which support the floor above and also act as reinforcing means for the hollow 15 wall.

A further object of my invention is to provide a device of the type described which makes use of novel spacing members for keeping the sides of the form separated. The 20 device is extremely simple in construction, and may be quickly disposed in position.

Other objects and advantages will appear as the specification proceeds, and the novel 25 features of the device will be particularly pointed out in the claims hereto attached.

My invention is illustrated in the accompanying drawings, in which:

Figure 1 is a sectional view through a hollow wall showing the forms in place,

Figure 2 is a perspective view of one-half 30 of one of the forms,

Figure 3 is a vertical section through the wall showing the form in position,

Figure 4 is a perspective view of a form 35 spacing member,

Figure 5 is a horizontal section through a slightly modified form,

Figure 6 is a horizontal section through an 40 other modified form of the device,

Figure 7 is a side elevation of the form used in Figure 6,

Figure 8 is a vertical section through the form shown in Figure 6, and further shows a 45 spacing member.

Figure 9 is a perspective view of a portion of the form shown in Figure 6, and

Figure 10 is a horizontal section of another modified form of the device.

50 In carrying out my invention I provide a form consisting of two identical halves.

Figure 2 shows one of these halves. The half comprises a supporting member made out of wire, sheet metal, or other suitable material, and comprises a flat portion 1 that extends from the top rails or plates 2 to a bottom rail 3. The flat portion 1 may be secured to the rails 2 and 3 by staples 4 or other suitable fastening means. It will be noted from Figure 2 that the portion 1 extends from the top of the rails 2 to the bottom of the rail 3. 55 The ends of the portion 1 are cut for forming portions 5 and 6. These portions are bent inwardly at an angle so as to extend between the top and bottom rails 2 and 3. Staples 7 may secure the portions 5 and 6 to the under- 60 surface of the lowermost rail 2 and the upper surface of the bottom rail or plate 3. The portion 5 has its very edge bent back upon itself to provide a flange 8. 65

In Figure 1 I show how the halves are placed opposite each other. It will be noted that the portion 6 extends from the portion 1 to which it is attached to a plane that is parallel with the portions 1 of the other halves of the forms. The pairs of forms may 70 be grouped together as closely as desired. I have shown this grouping to be such as to cause the portions 6 of adjacent pairs to almost touch each other.

The inclined portions 5 and 6 form recesses 80 for receiving concrete 9. This concrete is applied to the forms while it is still plastic, and it will imbed the wires of the forms to a degree sufficient to support the concrete until the latter hardens. The flanges 8 will become imbedded in the concrete. It will be noted that concrete columns will be provided in the recesses formed by adjacent pairs of 85 forms.

If desired, a wire member 10 may be placed in front of each recess and will act as a retainer for the concrete in the recess while the concrete is soft. The member 10 will also act as a reinforcing device for the concrete.

I have shown each form provided with a 95 paper backing 11 or other suitable material to prevent the concrete from filling the interior of the pairs of forms. The paper may be attached to the forms in any manner desired. The paper backing 11 does not ex- 100

tend over the portion 8, nor does it cover the outer half of the portion 6. The concrete can therefore imbed the portion 8 and the outer half of the portion 6.

Reference to Figure 4 shows a spacing member for keeping the halves of each form separated. As many of these spacers as desired may be disposed in place. Each spacer consists of a rectangular frame 12 that has hooks 13 for receiving a wire 14 of one form half. A supporting leg 15 is pivotally secured to the frame 12 at 16 and has a hook-shaped end 17 for receiving another wire 14 of the same form half. Figure 3 shows the position the frame 12 and the supporting wire 15 will assume in the wall structure.

In Figure 5 I show a slightly modified form which differs from that shown in Figures 1 and 2 to the extent that steps 18 are provided in the inclined portions 5 and 6 which will give greater rigidity to the forms and at the same time these steps may abut each other in adjacent pairs of forms so as to prevent any concrete from filling the space between adjacent form pairs. The steps 18 may be of any width desired and determine the width of the wall. The concrete may be placed between the forms and continue from one side of the wall to the other if desired, or the forms may abut each other, thus stopping the concrete at the vertices of the recesses. In all other respects the form of the device shown in Figure 5 is identical to that shown in Figure 1, and therefore the same reference numerals will be applied to similar parts.

In Figures 6 to 9 inclusive I show another modified form of the device. This form may be continuous or may be made up in sections. I provide two identical halves, and one of the halves is shown in Figure 9. It will be noted from this figure that a flat portion 25 has cuts 26 made at intervals for providing portions that may be bulged inwardly for forming angularly-extending portions 27 and 28. Figure 9 shows these portions extending inwardly, and further shows the portion 29 above the cut 26 that may be secured to the top rails 2. The inclined portions 27 and 28 may be large or small so as to provide large or small recesses. In Figure 6 I show large recesses 30 and small recesses 31. The tops and the bottoms of the forms are secured to the top and bottom plates 2 and 3 in the same manner as the other forms disclosed.

Concrete 32 is applied to the exterior surfaces of the forms, and fills the recesses 30 and 31 for forming supporting columns. Backing 33 disposed on the inside of the forms prevents the concrete from filling the space within the forms.

In Figures 6 and 8 I show a spacing member for the two sides of the forms, this member also acting as a supporting device. The member consists of two uprights 34 and 35 that are spaced from each other by cross-

pieces 36. The pieces 36 also act as bracing members. Horizontally-disposed pieces 37 and 38 connect the tops and the bottoms of the uprights 34 and 35. The uprights 34 and 35 extend above and below the pieces 37 and 38 and straddle the plates 2 and 3 so that they may be secured to the plates. The spacing member also acts as a stud for supporting the plates 2. The members may be spaced at intervals as shown in Figure 6, and as many as desired may be arranged in the hollow wall.

In Figure 10 I show a slightly modified form, this form differing from that shown in Figure 6 in only one particular. The inwardly-extending portions 27 and 28 carry projections 39 that extend into the recesses formed by the portions 27 and 28. The projections 39 embed themselves in the concrete while it is soft and act as reinforcing members for the concrete and also form a connection between the form and the concrete. The other parts are similar to those shown in Figure 6, and like reference numerals will therefore be applied.

Although I have shown and described several embodiments of my invention, it is to be understood that the same is susceptible of various changes, and I reserve the right to employ such changes as may come within the scope of the invention as claimed.

I claim:

1. A building form comprising a member having two halves, each half having a flat portion and inclined ends, certain of said ends being longer than others, the longer ends of adjacent members extending parallel with respect to each other.

2. A building form comprising a member having two halves, each half having a flat portion and inclined ends, certain of said ends being longer than others, the longer ends of adjacent members extending parallel with respect to each other, and means for spacing said halves from each other.

3. A building form comprising a member having two halves, each half having a flat portion and inclined ends, certain of said ends being longer than others, the longer ends of adjacent members extending parallel with respect to each other, said halves being lined with backing on their inner surfaces.

4. A spacing member for forms comprising a frame having hook-shaped portions for receiving a wire, and a supporting member pivoted to the frame and having a hook-shaped end.

5. A building form including a body part and having portions securable to the sides of the top and bottom plates of a wall, and having inclined portions receivable between the plates and forming a recess coextensive in length with the space between the plates and adapted to receive a cementitious material therein.

6. A building form comprising a member having two identical halves, each half having a flat portion and inclined ends, certain of said ends being longer than others, the longer 5 ends of adjacent members extending parallel with respect to each other, and the shorter ends presenting flanged edges. 70
7. A building form comprising two members having body portions disposed in spaced 10 relation and adapted to receive the top and bottom plates of a wall therebetween, said members having depressions therein extending between the plates and forming a recess coextensive in length with the space between 15 the plates and adapted to receive a cementitious material therein. 80
8. A hollow wall construction comprising two members disposed in spaced relation and adapted to receive the top and bottom plates 20 of a wall therebetween, said members having depressions therein extending between the plates, and a cementitious substance enveloping the members and filling the depressions, said substance, when hardened, forming reinforcing columns for the vertical walls and supports for the upper plate. 85
9. A building form comprising two identical members arranged in confronting relation, each having inclined ends, the inclined 25 portions of each member projecting toward the other member, one end of each member being longer than the other and extending beyond the shorter end of the other member and cooperating with the shorter end of the latter member for providing a material-receiving recess, certain of said ends having flanged edges adapted to retain a cementitious material in the recess. 90
10. A building form comprising two identical members arranged in confronting relation, each having inclined ends, the inclined portion of each member projecting toward the other member, one end of each member being longer than the other and extending 30 beyond the shorter end of the other member and cooperating with the shorter end of the latter member for providing a material-receiving recess, certain of said ends having flanged edges adapted to retain a cementitious material in the recess. 100
11. A building form comprising two members securable in spaced relation to the top and bottom plates of a wall and having recesses therein coextensive in length with the spaces between the plates and adapted to receive a cementitious material therein, and a backing disposed on the inner surfaces of said members serving to prevent the cementitious material from entering the space between the members when the material is applied to the form. 115
12. A building form comprising two identical members arranged in confronting relation, each having inclined ends, the inclined 35 120
13. A building form comprising two identical members arranged in confronting relation, each having inclined ends, the inclined portions of each member projecting toward the other member, one end of each member being longer than the other and extending beyond the shorter end of the other member and cooperating with the shorter end of the latter member for providing a material-receiving recess. 125
14. As an article of manufacture, a spacing and supporting member for wall constructions comprising uprights arranged in spaced relation, and pieces connecting the uprights together and disposed inwardly from the ends of the latter and cooperating with the projecting ends of the uprights for providing channel-shaped portions. 130
15. As an article of manufacture, a spacing and supporting member for wall constructions comprising uprights arranged in spaced relation, pieces connecting the uprights together and disposed inwardly from the ends of the latter and cooperating with the projecting ends of the uprights for providing channel-shaped portions, and reinforcing struts extending between the uprights. 135
16. In combination, an upper and lower plate forming part of a wall construction, uprights arranged on opposite sides of the plates and overlying the plate sides, horizontally-mounted pieces anchored to the uprights and bearing against the faces of the plates, and material-retaining forms secured to the uprights and plates. 140
